(57) **CLAIM**

The ornamental design for a controller for soldering iron, as shown and described.

DESCRIPTION

FIG. 1 is a first perspective view of a controller for soldering iron;

FIG. 2 is a second perspective view thereof;

FIG. 3 is a front view thereof;

FIG. 4 is a rear view thereof;

FIG. 5 is a left side view thereof, the opposite side being a mirror image of the side shown herein;

FIG. 6 is a top view thereof; and,

FIG. 7 is a bottom view thereof.

1 Claim, 4 Drawing Sheets
